(57) **CLAIM**

The ornamental design for a hood for an automobile, as shown and described.

DESCRIPTION

FIG. 1 is a front elevational view of a hood for an automobile showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front perspective view thereof; and,

FIG. 8 is a cross sectional view thereof taken along line 8-8 in FIG. 3.

The appearance of the bottom of the hood as seen in FIGS. 2 and 4 is for purpose of illustrating the boundaries of the exterior surface of the hood, and forms no part of the claimed design.

The cross sectional view of FIG. 8 is provided to clarify the exact contour or configuration of the exterior surface of the top portion of the hood, and no attempt is made to illustrate features of internal construction. The broken line showing of the bottom of the hood in FIG. 8 is for purpose of illustrating environmental structure and forms no part of the claimed design.
